UNITED STATES PATENT OFFICE.

HENRY BERRY, OF HUNTINGTON, AND JOSEPH BROWN BEACH, OF BRIDGEPORT, CONNECTICUT.

DESIGN FOR THE ORNAMENTATION OF SILVER PLATE.

SPECIFICATION forming part of Design No. 17,677, dated September 6, 1887.

Application filed June 25, 1887. Serial No. 242,549. Term of patent 7 years.

To all whom it may concern:

Be it known that we, HENRY BERRY and JOSEPH BROWN BEACH, citizens of the United States, residing, respectively, at Huntington and Bridgeport, in the county of Fairfield and State of Connecticut, have invented and produced a new and original Design for the Ornamentation of Silver Plate; and we do declare the following to be a full, clear, and exact description of the same, reference being had to the accompanying drawing, forming a part thereof.

The figure of the drawing represents our design.

The invention relates to ornamentation of silver plate; and it consists in the novel configuration of the surface thereof, hereinafter described.

In the accompanying drawing we have illustrated this design, which may be compared to frost-work, the body portions of which are

scroll-like, as indicated at A, and have feather-like extensions, as represented at B. The marking is granular and the grooving beveled or sloping, being deeper near the more clean-cut edge, and gradually shelving to the extremities of the feather extensions. Between the markings the intervals are smooth.

Having described this design, what we claim, and desire to secure by Letters Patent, is—

The design for a silver plate having an ornamentation consisting of the scroll-like granular frost-work markings, feather-like extensions, and the smooth intervals between the markings, as shown and described.

In testimony whereof we affix our signatures in presence of two witnesses.

HENRY BERRY.
J. BROWN BEACH.
